UNITED STATES PATENT OFFICE

SAMUEL E. WISHARD, OF LUDLOW, CALIFORNIA

TRACK RECORDER

Application filed October 7, 1931. Serial No. 567,499.

This invention relates to devices known as track recorders, the primary object of the invention being to provide a machine by means of which it is possible to determine 5 and record the transverse contour of the treads of the rails of railway tracks.

An important object of the invention is the provision of means whereby the contours of both rails of a track may be measured and 10 recorded at a single operation.

A further object of the invention is the provision of a track recorder which may be operated to determine the wear on the rail heads on the outer rails of curves, and the 15 amount of battering and widening of rail heads on the inner sides of the inner rails of curves.

A still further object of the invention is the provision of means for recording variations of track elevations at curves, to the end 20 that the track may be maintained in an even and level condition.

With the foregoing and other objects in view, which will appear as the description 25 proceeds, the invention resides in the combination and arrangement of parts and in the details of construction hereinafter described and claimed, it being understood that changes in the precise embodiment of the invention 30 herein disclosed, may be made within the scope of what is claimed, without departing from the spirit of the invention.

Referring to the drawings:

Figure 1 is a side elevational view of a 35 track recorder constructed in accordance with the invention.

Figure 2 is a plan view thereof.

Figure 3 is an end elevational view of the 40 track recorder, parts thereof being shown in section.

Figure 4 is an enlarged sectional view taken longitudinally through the support and table of the track recorder.

Figure 5 is a sectional view taken on line 45 5-5 of Figure 2.

Figure 6 is a sectional view taken on line 6-6 of Figure 2.

Referring to the drawings in detail, the 50 reference character 5 designates the body portion of the usual hand car used by rail-

way track repairmen, the body portion being supported on the axles 6 that are mounted in bearings 7, and on which the wheels 8 of the hand car operate.

The device embodies a bar 9 which is secured to the under side of the body portion 5, by means of the bolts 10, the bar 9 having downwardly extended portion 11 defining spaced supporting arms. Pivots connected to the downwardly extended bars or supporting arms 11 are spaced forwardly extended bars 12, the forward ends of the bars 12 being held in spaced relation by means of the bolts 13.

The reference character 14 designates connecting links that have pivotal connection with the bars 12, and extend upwardly where they connect with the arms 15, which are secured to the shaft 16 journaled in the bearings 17 that are secured to the upper surface 65 of the body portion 5, as clearly shown by Figure 3 of the drawings.

An operating lever indicated at 17, is connected with the shaft 16 and affords means whereby the device may be moved into and 70 out of operation.

Supported between each pair of forwardly extended bars 12, is a table 18 over which the webs 19 operate, the webs being wound on the rolls 20, which are mounted between the 75 bars 12, to be wound onto the rolls 21 also mounted between the bars 12 near the forward ends thereof.

Secured to one end of the shaft 12' on which the rolls 21 are mounted, is a gear 22 that is in mesh with a small gear carried by the gear 23, the gear 23 being in mesh with the gear 24 forming a part of the main sprocket 25. Rotary movement is transmitted from the wheel 8 at the front end of the body portion 5, through the medium of the chain 26, which operates over the sprocket 27 mounted on one end of the shaft 12'.

In connection with the gearing, it might be stated that the ratio of gears is such as to cause approximately one inch of each web to be fed across the tables 18 with every 33 feet of travel of the device over the rails being gauged.

Secured to one of the bars 12 at each side 100

of the body portion 5, is a downwardly extended arm 27 formed with a reduced portion or axle 28, on which the wheels 29 are mounted.

5 These wheels 29 are formed with flanges and fit over the outer edges of the rails of the track, the rails being indicated by the reference character 30.

The reference character 31 designates a rod 10 that extends inwardly from each arm 27, to overlie the rails of the track over which the device moves. The rods 31 extend into the hollow arms 32 that extend inwardly from the pivoted arms 33, the hollow arms 32 being formed with flanges 34 against which the coiled springs 35 engage, the coiled springs 35 being secured to the arms 27, so that the arms 33 will be moved towards the arms 27, as the springs contract.

20 These arms 33 are formed with angularly disposed shafts 36 in which the wheels 37 are mounted, the wheels 37 contacting with the opposite edges of the treads of the rails.

As clearly shown by Figure 5 of the drawings, these arms 33 are formed with right angled end portions 38 that overlie the tables 18 and webs operating thereover. Markers 39 are adjustably supported near the free ends of the right angled portions 38, and are so constructed that they contact with the webs to mark the webs, as the webs pass thereunder.

An ear 40 extends from one of the pivoted arms 33 and provides a connection for the rod 41 which also has connection with the bar 42. The bar 42 is pivotally mounted on the bracket 43, and has pivotal connection with the rod 44, at 45. The rod 44 extends transversely across the table and web at the 49 opposite side of the body portion, the rod operating through the bearing 45.

Carried by the rod 44, is a marker 46 that marks the web passing thereunder.

From the foregoing it will be obvious that 45 as the rail head at either side of the rail is worn, the arms 33 carrying the wheel 29 operating over the worn portion, will move laterally operating the marker to indicate an irregular line on the web, showing such wear.

50 Should the normal gauge or distance between the rails be varied, the connecting rod 41 will be operated to move the rod 44 and marker 46 connected therewith, causing an irregular line to be formed under this marker.

55 By examining these lines it is obvious that a repair man may readily determine the gauge of the rails, and wear of the rail heads.

Secured to one of the bars 12, is an upwardly extended supporting arm 47 which is 60 formed with a groove to receive the marker arm 48, which is provided with teeth 49 extending upwardly therefrom and disposed near one end thereof.

Carried by the arm 48, is a marker 50 that 65 contacts with the web operating over the

table, to mark a line thereon, as the webs move under the marker.

Pivots mounted above the marker arm 48, is a weighted segment 51, which is formed with teeth that engage the teeth 49. This segment 51 is pivotally mounted on the upstanding arms 52, and is designed to swing by gravity.

70 Thus it will be seen that as the device tilts laterally, owing to a sunken condition of one of the rails of a railway track, the segment 51 will swing laterally moving the marker arm 48 and marker connected therewith, causing an irregular line on the web.

Having thus described the invention what 80 is claimed is:

1. A track recorder comprising a body portion movable over the rails of a railway track, a frame mounted under the body portion, an arm mounted on the body portion, a wheel 85 on the arm for moving over a railway rail, an arm extending laterally from the first mentioned arm, a movable arm, a wheel on the movable arm and engaging the rail over which the device is moving, a tubular arm extending from the movable arm, yieldable 90 means for normally urging the arms towards each other, and a marker operated by the movable arm.

2. A track recorder comprising a body portion 95 movable over the rails of a railway track, a frame mounted under the body portion, arms depending from the body portion, one of the arms being laterally movable, wheels 100 on the arms for gripping the opposite sides of a rail, a web operating over the body portion, and a marker carried by one of the arms and movable therewith, for marking on the web.

3. A track recorder comprising a body portion 105 movable over the rails of a railway track, a vertically adjustable frame mounted under the body portion, a table mounted on the frame, a web operating over the table, an arm extending downwardly from one side of the frame, a wheel on the arm and engaging a rail over which the body portion moves, a rod extending laterally from the first mentioned arm, a movable arm, a hollow arm extending from the movable arm, and operating 110 over the first mentioned laterally extended arm, a wheel mounted on the movable arm and operating over the rail, the upper end of the movable arm overlying the table, and a marker carried by the upper end of the movable arm to mark on the web, as the movable arm moves laterally.

In testimony that I claim the foregoing as my own, I have hereto affixed my signature.

SAMUEL E. WISHARD. 125
